DOLLY FOR WASHING MACHINES

John Holroyd Brook, Toronto, Ontario, Canada

Application March 4, 1947, Serial No. 732,295

1 Claim. (Cl. 68—134)

1

The invention relates to improvements in dollies for power driven washing machines and has for its general object to provide a more efficient and serviceable agitator of this type for use in washing machines of a known construction.

The invention essentially concerns an agitator which is oscillated about a vertical axis centrally of the tub by a suitable power driven mechanism. In particular the invention has as an object to provide an agitator with radial blades having on each side an arrangement of vertical and horizontal webs or ribs which form a group of pockets. Preferably diametrically opposite blades are employed and they are reversely curved in radial direction. The webs or ribs function in a manner to keep the articles to be cleaned away from the radial wall of a blade so that as the blade impinges the articles the liquid is forced into them with an effective washing action. The pockets act like suction cups on the articles forcing the soapy water through them in order that they may be properly cleaned by the action of the soap.

The invention consists in the novel combination and arrangement of parts as described in the ensuing specification and shown in the accompanying drawing which forms a part thereof.

In the drawing, Fig. 1 is a sectional plan view of an agitator constructed in accordance with the present invention and taken on line 1—1 of Fig. 2.

Fig. 2 is a vertical section of the agitator taken substantially on the line 2—2 of Fig. 1.

The agitator of the present invention is of the kind employed in standard types of power driven washing machines in which the tub has a central spindle which extends upwardly from its base to carry the agitator. The spindle is oscillated about its axis by suitable mechanism driven by an electric motor and controlled by a hand-operated clutch. The tub, spindle and driving mechanism are not shown in the drawing since they do not form a part of the present invention.

In carrying out the instant invention the agitator is provided with the usual hub 5 to enable it to be sleeved on the tub-spindle. The bore 6 of the hub is a loose fit on the spindle and in ordinary practice has a reduced upper end 7 of a square cross section to form a driving connection with the distal end of the spindle, which is of a like cross section. This construction enables the agitator to be demounted at will.

The hub is united with a base member 8 of disk-like configuration which encircles the hub clear of the floor of the tub. The blades, denoted as a whole by the numeral 9, extend radially of the hub and upstand from the base member 8 as a unit therewith. Preferably there are two such blades, diametrically arranged and each

2

provided with an imperforated wall 10. Desirably the walls 10 are curved in radial direction and the curvatures are reversely disposed with respect to a diametrical plane through the blades.

- 5 At each side of a blade there is provided a series of vertical and horizontal intersecting webs or ribs 11 which form pockets 12 in group formation. Accordingly there is provided on opposite sides of the blades a multiplicity of comparatively small pockets each of a general rectangular shape. The pockets are shallow and the ribs are thin flat elements of uniform depth. The horizontal ribs throughout their length follow the curvature of the walls 10.
- 15 When the agitator is mounted on the tub-spindle and motivated the blades are turned to and fro in well known manner in a washing operation. In this operation the pockets of the blades set up an effective turbulence of the cleansing fluid, and the clothes are impinged by the ribs and thereby spaced from the walls 10, which allows the fluid to penetrate the clothes thoroughly so that dirt is washed out by the action of the soap in an effective manner.
- 20 The invention provides an agitator of the dolly type which is highly satisfactory in use and one which can be manufactured at low cost.

What I claim is:

- An agitator for a washing machine comprising a hub for fitting on a vertical spindle driven with an oscillatory motion, a disc-like base member encircling the hub and rigid therewith, and a pair of diametrically opposite blades carried by said hub and joined to said base member to upstand therefrom, each blade consisting of an imperforated radial wall, and intersecting ribs on each side of the radial wall, said ribs being uniformly spaced in vertical and horizontal series in an intersecting manner to project from the sides of the radial wall for a uniform distance throughout the areas of said sides to form shallow suction pockets.
